BACK PRESSURE VALVE

Billy J. Graham, Midland, Tex., assignor to Jersey Production Research Company, a corporation of Delaware

Filed Dec. 21, 1959, Ser. No. 860,811

8 Claims. (Cl. 166—127)

The present invention is broadly concerned with an improved technique for cementing, particularly squeeze cementing in well boreholes. The invention is more specifically concerned with an improved low pressure, easily drillable retainer back pressure valve mechanism or assembly by which the pressure on the cement may be retained for the desired time period until the cement has properly set. In essence the assembly comprises an upper retrievable section and a lower non-retrievable section. The lower non-retrievable section is detached and may be readily removed by drilling. A particular feature of the present invention comprises a frangible insert positioned at the lower end of the non-retrievable section which insert may be removed or broken by dropping a hollow bar or piece of lead pipe or equivalent which permits a ball to seat in a valve seat thereby retaining the pressure on the cement.

In the drilling art it is well known to use various methods and techniques for sealing off undesirable formations. For example, in a well in which casing has been set and in which there exists perforations into an oil-bearing formation at times oil will cease to produce and water will be produced through these perforations. Under these circumstances various techniques have been utilized for squeeze cementing through these perforations into the formation about the casing in order to prevent further entry of undesirable water or brine into the casing. One problem in this type of operation is to maintain the desired pressure on the cement until the same has set in order to prevent the back flowing of the cement into the casing which would result in an undesirable cementing operation.

The apparatus and process of the present invention may be readily understood by reference to the drawing illustrating one embodiment of the same. Referring specifically to the drawing, the squeeze cementing apparatus of the present invention is shown attached to the lower end of drill pipe or tubing 1 by means of a suitable tool joint 13. Tool joint 13 is characterized by having a lower flat surface or shoulder 16.

The apparatus is shown positioned within casing 2 near the bottom of the borehole wherein perforations 19 provide communication from formation 18 to within casing 2. The apparatus or assembly comprises an upper retrievable section comprising a hollow cylindrical mandrel 14 about which is positioned an expandable packing element 3 which may be made of rubber or other suitable packing material which will expand upon compression so as to seal off the annular area between the assembly and the inner wall of the casing. The area within the hollow cylindrical mandrel 14 communicates to the area within the pipe string 1 thus permitting the flow of fluid or cement downwardly. Positioned below packer 3 on the exterior of the mandrel is an expandable slip assembly 21, including slip cage 23, ring means 24 non-rotatably mounted in the interior of the slip cage, and springs 4 which extend outwardly from slip cage 23 and maintain frictional contact with the inner wall of the casing. Serated or toothed latching slips 15 are positioned on the outer surface of slip assembly 21 by conventional means. Tapered locking elements 17 are positioned on the outer surface of the mandrel and will function as hereinafter described. The lower end of the mandrel is connected to and communicates with the lower non-retrievable section. The non-

2

retrievable section includes a short nipple section 20, the lower end of which comprises a downwardly facing shoulder which forms valve seat 7, and an outwardly flaring portion below the valve seat. A circular cup 30 is attached to the lower edge of the outwardly flared portion of nipple section 20. The upper retrievable section and the lower non-retrievable section are attached to one another by means of shear pins 5. Ports 12 in the mandrel provide communication from within the tubing and mandrel to the outer annular area between the assembly and the casing.

As mentioned, the lower section of the assembly comprises the valve seat 7, the seal or cup-type packer 11, the slip 6 mounted on the packer and nipple 20 in which the valve seat 7 is formed, and also the cup attached to the bottom of the outwardly flaring portion of nipple 20 below the valve seat 7, the frangible bottom 22 of the cup and the ball valve 9 and guides holding the ball off its seat. This assembly constitutes the frusto-conical valve structure. Frangible insert 22 is provided at the lower end of the cup 30 which insert contains perforations 10. A sealing or valve shutoff ball 9 is positioned above the insert in a fixed position by means of upwardly extending guides 8.

In operation the assembly is lowered through the casing to the desired position which normally is immediately above the formation to be squeeze cemented off. In lowering the assembly friction contact is maintained between springs 4 and the inner surface of the casing. After the apparatus has been lowered to the desired point the tubing is rotated thereby causing slip cage 23 of assembly 21 to move upward, which forces slips 15 to expand outwardly. The toothed surface or edges engage the inner surface of the casing, thereby retarding downward movement of the same. In essence this upper section assembly of the present invention comprises a conventional hook wall packer assembly. After the toothed surface of slips 15 have engaged the inner surface of the casing the tubing is lowered thereby causing the shoulder 16 to exert compressive thrust on the upper area of packer 3. This expands packer 3 so as to make contact between the assembly and the inner surface of the casing thereby preventing communication from below the packer to above the packer. Also tapered locking elements 17 exert a downward thrust on slips 15 thereby locking these latter elements against the casing.

At this point a hollow drill bar, a piece of lead pipe or other heavy material is dropped down within the drill stem which falls against insert 22 thereby shattering the same and removing it. It is to be noted that the upwardly extending guides 8 are attached only to the insert 22 and are thereby removed when 22 is broken thereby permitting ball 9 free movement. It is to be also noted that retaining guides 8 extend close enough to the surface of the seat so that ball 9 will not be free until 22 is shattered.

The squeeze cementing is then carried out by forcing the cement downwardly within the tubing through the assembly into the formation 18 through perforations 19. During this operation it is to be noted that there exists no differential pressure across the assembly due to the pressure equalizing holes 12 in the running tool. After the squeeze cementing operation has been completed and the surface pressure released then the valve ball 9 which is preferably a Bakelite or other type of rubber material is set in the valve seat thereby preventing upward flow of the cement. The upward pressure also expands the rubber seal 11 and sets slips 6 against the casing which prevents upward movement of the lower section of the assembly. This maintains the desired pressure on the cement as it sets.

An upward thrust is exerted by the string which will shear off shear pins 5 permitting the raising of the upper retrievable section of the assembly and retaining the lower non-retrievable section of the assembly in the bore-hole for maintaining the desired high pressure on the cement within the formation until the cement has properly set.

As pointed out heretofore, when the assembly is run in the hole the ball is retained away from the seat by the frangible insert and by guides attached to the insert. At such time when the tool is run in to the desired depth a hollow drillable bar or piece of lead pipe is dropped. This bar shears loose the small insert in the junk pusher to which are fastened the guides. Both will fall to bottom and the ball is free to seat in the valve seat. The ball is of a plastic material lighter than oil and thus will float up against the seat at any time fluid is not being pumped through the tool. Thus it acts as a back pressure or check valve.

The slips 6 in the lower section are preferably molded into the rubber seal 11 and fitted by tongue and groove into the top retainer piece which is preferably made of brittle cast iron with hardened teeth. All the other parts of the lower section of the tool are preferably made of magnesium and rubber which are both easily drillable. All parts not having a pressure differential are preferably criss crossed with grooves so that these parts will readily break into small pieces and be circulated out of the hole while the tool is being drilled up. The easy drillability of this tool is a most important factor since it can be drilled in about one hour whereas conventional non-retrievable retainers take several hours and longer to remove, especially at shallow depths. The assembly of the present invention can also be used as a low pressure squeeze tool in conjunction with a rotating or reciprocating circulation control unit.

What is claimed is:

1. Improved assembly for positioning in a borehole to maintain back pressure in said borehole which comprises an outwardly and downwardly flared conical structure thus defining a frusto-conical valve structure, an opening in the upper area of said structure permitting communication from without said structure to within said structure, a circular cup attached to the bottom of said structure, the base of said cup being frangible, a guide extending upwardly from said base, and a ball positioned in the area defined by said guide, said base and the walls of said cup whereby said ball is locked into a relatively fixed position, the density of said ball being less than the density of borehole fluid, means for fracturing said base thereby permitting movement of said ball within said structure, whereby as fluid flows downwardly through said opening, free passage of the same is permitted; but, on back flow of fluid said ball seats in said structure thereby preventing back flow of said fluid.

2. Apparatus as defined by claim 1 wherein an expandable packing element is circumferentially positioned on the exterior of said conical structure.

3. Apparatus as defined by claim 2 wherein a toothed slip is embedded in said packing element, the teeth of which are adapted to engage the wall surrounding the assembly and prevent vertical movement of the same.

4. An improved apparatus for positioning in a borehole casing to conduct a squeeze cementing operation and to

5 maintain back pressure in said hole until the cement has set which comprises an upper retrievable section and a lower non-retrievable section, said upper retrievable section being adapted to be attached to the lower end of a drill string by suitable means in a borehole adjacent the formation to be cemented, said upper retrievable section comprising a hollow mandrel having interior communication with the interior of said drill string, a packer element disposed circumferentially without said mandrel adapted to be expanded upon compression, slip means on said mandrel, including a slip cage, guide springs extending outwardly from said slip cage to maintain frictional contact with the inner wall of said casing through which the assembly is lowered, toothed slip means in said cage adapted to be expanded and extend outwardly from the exterior of said mandrel and to contact the interior of the casing thereby preventing vertical movement of the assembly, a lower non-retrievable section attached to said upper retrievable section by means of a pipe section connected by shear pins, said lower non-retrievable section comprising an outwardly and downwardly flared conical structure defining a frusto-conical valve structure, an opening in the upper area of said structure permitting communication from within said structure to within said pipe section to within said mandrel, a circular cup attached to the bottom of said structure, the base of said cup being frangible, a guide affixed to said base extending upwardly from said base and a ball positioned in the area defined by said guide, said base and the walls of said cup whereby said ball is locked into position, the density of said ball being less than the density of said cement, means for passing a heavy object downwardly through said drill stem through said mandrel and into and through said structure to break said frangible base, thereby permitting movement of said ball within said structure, whereby as cement flows downwardly through said opening, free passage of the same is permitted; but, on back flow of cement said ball seats in said structure thereby preventing back flow of said cement.

40 5. Apparatus as defined by claim 4 wherein said frangible base contains perforations.

6 6. Apparatus as defined by claim 4 wherein said pipe section contains perforations thereby permitting communication from within said pipe section to the annular area about the apparatus and between the packer element disposed without said mandrel and the exterior area of said structure.

7. Apparatus as defined by claim 4 wherein an expandable packing element is circumferentially extended on the exterior of said structure.

8. Apparatus as defined by claim 7 wherein a toothed slip is embedded in said packing element, the teeth of which are adapted to engage the walls surrounding the assembly and prevent vertical movement of the same.
